Inventor:

FRED FORMANECK,

by Robert Burns.
Atty.

UNITED STATES PATENT OFFICE

FRED FORMANECK, OF CHICAGO, ILLINOIS

THERAPEUTIC HEATING APPLIANCE

Application filed January 13, 1930. Serial No. 420,366.

This invention relates to an electrical heated means for holding and maintaining medicinal pads and like applications in place upon a person to be treated. And this improvement has for its object:

To provide a simple and substantial formation and combination of such type of appliances adapted to afford an efficient and uniform heating effect and also adapted for ready and effective attachment in place on the person of a party using the same, all as will hereinafter more fully appear.

In the accompanying drawings:

Fig. 1 is a sectional elevation on line 1—1, 15 Fig. 2, of an electric heating appliance embodying this invention.

Fig. 2 is a section on line 2—2, Fig. 1 of the same.

Like reference numerals indicate like parts 20 in both views.

In the preferred form of this invention, the enclosing shell or housing has the form of a shallow shell comprising a circular wall 1 and dished top and bottom walls 2 and 3, 25 with the dished bottom wall 3 in connection with a lower marginal rim 4 of the wall 1 providing an open bottom receiving chamber 5 the roof of which is of a sphero-concave form for a medicated pad or other form of medic- 30 amental substance intended for use in local treatment of various parts of the human body. In the present construction the upper marginal rim or seam 6 of the wall 1 is formed with a plurality of slits or orifices 7 to receive 35 a tape or bandage by means of which the appliance is secured in place on the part of the person using the same.

Arranged centrally in the interior of the enclosing shell or casing of the appliance, is an 40 electrical heating unit of the resistance type, preferably of a construction as follows:

A pair of outer circular sheets 8 and 9 of 45 non-electric material, usually mica, in separated relation, provides a protecting en- closure for an inner core 10 of non-electric material, usually mica, which core is formed into a pair of opposed semi-circular sections, with the opposed curved and straight mar- 50 gins thereof formed with a plurality of notches 11 in spaced relation, and into which

the windings of the resistance wire 12 is engaged and held in proper relation one to the other as illustrated in Fig. 2.

The above mentioned electrical resistance wire 12, by which the heating of the appliance 55 is effected, will usually be formed of the well known nichrome alloy, and in a ten watt element will contain nine feet #43 B. S. gauge, of such wire, and in a fifteen watt element will contain a like nine feet #45 B. S. gauge, 60 of said wire. The resistance wire windings 12 on the respective semi-circular sections of the core 11 are in series, with the respective terminal ends of such windings electrically connected to the line wires of an ordinary flexible 65 conducting cord 13, which is employed to conduct the electromotive force from a wall socket or the like to the present appliance.

As usual in portable electrical appliances 70 of this and other types the flexible conducting cord 13 will be substantially anchored by a holding bushing 14, in the wall 1 of the appliance, with a view to avoid accidental and injurious strain on the heating unit in actual 75 use of the appliance.

All vacant spaces in the interior of the 80 appliance are preferably filled with a mass 15 of loose asbestos.

Having thus fully described my invention 85 what I claim, is:—

1. In an electrical heating appliance of the type herein described, the combination of a closed containing housing formed with a dished bottom wall providing a containing cavity the roof of which is of a sphero-concave 85 form, a medicament carrying means in said cavity, an electric heating unit arranged within the housing adjacent to said bottom wall, and a flexible conducting cord attached to the wall of the appliance with its line wire 90 connected to the terminals of the electric heating unit.

2. In an electrical heating appliance of the type herein described, the combination of a closed containing housing formed with a dished bottom wall providing a containing cavity the roof of which is of a sphero-concave 95 form, a medicament carrying means in said cavity, an electric heating unit arranged within the housing adjacent to said bottom 100 wall.

wall and comprising a pair of round non-electric sheets in spaced relation, a non-electric sheet or core arranged between said outer sheets, and a resistance wire wound upon said core or sheet, and a flexible conducting cord attached to the wall of the appliance with its line wires connected to the terminals of the electrical heating unit.

3. In an electrical heating appliance of
10 the type herein described, the combination of a closed containing housing formed with a dished bottom wall providing a containing cavity the roof of which is of a sphero-concave form, a medicament carrying means in said cavity, an electric heating unit arranged within the housing adjacent to said bottom wall and comprising a pair of round non-electric sheets in spaced relation, a non-electric sheet or core arranged between said
15 outer sheets and formed into a pair of semi-circular sections the opposed edges of which are formed with a series of notches, a resistance wire wound upon said sections and having holding engagement in the notches, and a flexible conducting cord attached to the wall of the appliance with its line wires connected to the terminals of the electrical heating unit.

4. In an electric heating appliance of the
30 type herein described, the combination of a closed containing housing formed with dished top and bottom walls, the dished bottom wall providing a containing cavity the roof of which is of a sphero-concave form, a medicament carrying means in said cavity, an electric heating unit arranged within the housing adjacent to said bottom wall, and a flexible conducting cord attached to a wall of the appliance with its line wires connected to the terminals of the electric heating unit,
35 40 the seam between the side and the top wall of the housing having slits for engagement with an attaching tape or bandage.

5. In an electric heating appliance of the
45 type herein described, the combination of a closed containing housing formed with dished top and bottom walls, the dished bottom wall providing a containing cavity the roof of which is of a sphero-concave form, a medicament carrying means in said cavity, an electric heating unit arranged within the housing adjacent to said bottom wall and comprising a pair of round non-electric sheets in spaced relation, a non-electric sheet or core arranged
50 between said outer sheets, a resistance wire wound upon said sheet or core, and a flexible conducting cord attached to a wall of the appliance with its line wires connected to the terminals of the electrical heating unit, the seam between the side and the top wall of the housing having slits for engagement with an attaching tape or bandage.

In testimony whereof I hereunto affix my signature.
